United States Patent Office

Des. 226,612
Patented Apr. 3, 1973

226,612

TELEPHONE COVERS

Barbara H. Robinson, 9955 Miraflores Drive,
Baton Rouge, La. 70815

Filed Apr. 29, 1971, Ser. No. 138,849

Term of patent 14 years

Int. Cl. D14—03

U.S. Cl. D26—14 A

FIG. 1.

FIG. 1 is an isometric view of a telephone cover showing my new design; and

FIG. 2 is a modified embodiment of the telephone cover illustrated in FIG. 1.

The undisclosed rear portions of the telephone cover are unornamented.

I claim:

The ornamental design for telephone covers, substantially as shown and described.
